UNITED STATES PATENT OFFICE

GEORGE W. GERLACH, OF CUMBERLAND, IOWA.

BLOCK-SIGNAL CONTROL SAFETY APPLIANCE FOR LOCOMOTIVES.

1,135,574.

Specification of Letters Patent. Patented Apr. 13, 1915.

Application filed May 6, 1913. Serial No. 765,860.

To all whom it may concern:

Be it known that I, GEORGE W. GERLACH, citizen of the United States, residing at Cumberland, in the county of Cass and 5 State of Iowa, have invented certain new and useful Improvements in Block-Signal Control Safety Appliances for Locomotives, of which the following is a specification.

My present invention relates to new and 10 useful improvements in safety appliances for railways and more particularly to an appliance or device which, when installed, will make up part of the equipment of a locomotive and which will operate, in connection with contact shoes positioned along the track, to automatically stop any trains so equipped in case of danger and the object of my invention is to provide an appliance which, in conjunction with a block 15 signal system, will automatically apply the air brakes of the train in case of danger.

In my copending application filed May 6, 1913, and bearing the Serial No. 765,859 I have fully described and claimed a particular type of block signal system and the hereinafter described safety appliance is particularly adapted for use over roads employing this block signal system although its range of usefulness is in no way limited 20 to such roads. In the above noted application I disclosed a special type of contact carrying member which, under all conditions which might prove dangerous to traffic, will be moved to active position and one 25 of the objects of my present invention is to provide, in connection with normally open circuits controlling the engineer's valve of the locomotive, circuit closers in the form of flexible brushes or shoes for engagement 30 with the contacts carried by said devices when the latter are moved to active position.

A further object of my invention is to provide an electric current generator for generating the current necessary to operate 45 the controlling mechanism of the engineer's valve when the circuits of said mechanism are closed by the engagement of the brushes with the contacts carried by the contact members positioned along the track. And 50 a still further object of my invention is to provide means for driving the generator, so constructed and arranged that the throttle valve of the engine can not be opened without setting the generator in motion, although when the generator is once started 55

the mere closing of the throttle valve will not be sufficient to stop the same.

With these and other objects in view, my invention will be more fully described, illustrated in the accompanying drawings, and 60 then specifically pointed out in the claims which are attached to and form a part of this application.

In the drawings: Figure 1 is a diagrammatic perspective view of a conventional 65 form of locomotive equipped with my safety appliance, showing the same engaging the contacts of a contact carrying member such as is employed in connection with my block signal system, as set forth in my previously 70 referred to application; Fig. 2 is a sectional view through the contact carrying member and brush carrying housing of the locomotive, showing the brushes of the locomotive in engagement with the contacts of the signal system, the latter being shown in active 75 position; Fig. 3 is a detail sectional view on the line 3—3 of Fig. 2; Fig. 4 is a side elevation of a conventional form of engineer's valve, showing the manner in which I 80 employ a motor for automatically moving the valve to service position upon closing of the circuits of the safety appliance; Fig. 5 is a section on the line 5—5 of Fig. 4, looking 85 downwardly toward the valve to more clearly show the manner in which the motor operates the valve.

Corresponding and like parts are referred to in the following description and indicated in all the views of the drawings by the 90 same reference characters.

In order to insure a clear and complete understanding of my safety appliance and its manner of operation I have illustrated the same in connection with a conventional 95 form of locomotive 10 having a throttle valve 11 operatively connected by a link 12 to the usual form of throttle valve lever 13. The locomotive and train are equipped throughout with air brakes of the usual or any preferred type controlled by the engineer's valve shown conventionally at 14. As all these parts may be of the usual or any desired type any detailed description of the same is unnecessary.

In installing my appliance a pipe 15 is led from the steam dome 16 of the locomotive boiler to the inlet port of a steam turbine 17 having a revolving rotor keyed or otherwise secured upon a shaft 18. This 110

shaft is either operatively connected with or forms a continuation of the shaft 19 of an electric generator 20 of conventional type. It will therefore be apparent that as long as steam passes through the pipe 15 to the turbine the driving of the turbine will drive the generator and thus afford an ample supply of current for energizing the various circuits of my safety appliance. 10 The turbine and generator may be located at any convenient point upon the locomotive either within or without the cab thereof but a portion of the pipe 15 will in any case preferably run through the cab and be provided with a valve 21 of the turn plug type controlling the admission of steam through the turbine. The stem 22 of this valve carries a crank arm 23 and a link 24 is pivotally connected at one end to the free end of this crank arm and slotted at its other end as shown at 25 for sliding engagement with a pin 26 carried by the intermediate portion of the throttle lever 13. The free end of the link 24 is rounded or otherwise shaped 26 to form a handle 27 by which said lever may be manually operated to open or close the valve 21.

Both the throttle valve and valve 21 are arranged to be opened by rearward movement of their levers 13 and 24, respectively, and the slot and pin connection between the said levers is so arranged that when both valves are closed any swinging of the throttle lever 13 will cause a corresponding swinging 35 of the valve link 24. For this reason it is impossible to open the throttle valve without opening the valve 21. At the same time, because of the provision of the slot 25, the throttle valve lever 13 may at any time be 40 swung forwardly to close the throttle valve without in any way affecting the valve link 24. It will therefore be apparent that the throttle valve cannot be opened without opening the valve 21 controlling the passage 45 of steam to the turbine and that at the same time the closing of the throttle valve does not close the valve 21. However, if the throttle valve is closed, the valve link 24 may be manually moved forwardly to close 50 the valve 21.

This construction and arrangement of parts is of great importance as it insures a continuous operation of the turbine and consequently of the generator unless the steam 55 valve 21 is intentionally closed and this valve even, cannot be intentionally closed, as long as the throttle valve is open. Because of this, the turbine and generator will both operate, under ordinary conditions, when a 60 train is passing down grade with its throttle valve closed, the intention being that the turbine shall be driven at all times when the locomotive is on a run and not stop at each station or at each place where the throttle 65 valve is closed. This generator furnishes

the necessary current to, under proper conditions, operate a motor 28 which, when energized, will move the valve handle of the engineer's valve to service position. In Figs. 4 and 5 I have illustrated the manner in which the motor 28 is operatively connected to the engineer's valve 14. As there shown, the motor is supported above the engineer's valve by a bracket 29 in such a manner that the motor shaft 30 is in alignment with the valve stem 31 which carries the valve handle 32. As is usual in engineer valve construction the swinging of this valve handle is limited by stops 33 and 34 carried by the top of the valve casing and the service application of the valve takes place when the valve handle is swung to a position intermediate between these stops. In order to provide operative connection between the motor and valve handle I provide the motor 35 shaft 30 with a disk 35 having a concentrically formed slot 36 through which is passed a pin 37 carried by the valve handle 32. The disk is also provided with a radially extending lug 38 adapted in one position to engage 40 against the stop 33 and limit further rotation of the disk under the influence of the motor.

It will of course be clear, inasmuch as under normal conditions the motor 28 is de- 95 energized, that the connection between the motor and valve handle 32 will in no way interfere with the manual actuation of said valve handle to permit any desired application of the valve as the motor shaft will turn 100 freely when the motor is deenergized. As soon however, as the motor is energized, the disk 35 will rotate, from whatever position it happens to occupy, in the direction of the arrow in Fig. 5, until the pin 37 seats in the rear end of the slot 26 when further rotation of the disk will turn the valve handle 32, this movement being continued until the stop 38 of the disk engages the stop 33 of the valve casing. This stop 38 is so arranged 105 that this will occur when the valve handle has been moved to service position. The slot 36 is so formed that when the valve handle has been moved to service position by rotation of the disk 35, the valve handle may be 110 manually moved ahead to emergency position, if necessary, the pin 37 moving freely from the rear to the forward end of the slot, for this purpose.

The above constitutes the chief or primary part of my present invention, the remainder consisting in the provision of the necessary circuits between the generator and motor and circuit closers included in said circuits in the form of contact brushes or 120 shoes adapted to be engaged by the contacts of a block signal system when the said latter contacts are moved to active position. It will of course be apparent that the construction of the circuit closers and manner of 125 130

mounting the same, will vary considerably according to the type of block signal system installed in the road over which the locomotive equipped with my safety appliance is to operate. For this reason, I have illustrated, in Figs. 1, 2 and 3 of the drawings, a particular type of circuit closer or contact shoe and manner of mounting the same which is especially adapted for operation in conjunction with a specific form of contact carrying member employed in the block signal system invented by me and fully disclosed in a copending application. The contact carrying member of said block signal system is also shown in Figs. 1 and 2 in connection with the circuit closers of my safety appliance and to insure a clear understanding of the operation of the latter I will first explain in a general way, the construction of the contact carrying member of the block signal system.

As fully explained in my copending application, several times referred to, my block signal system includes a track divided into a plurality of blocks, the rails of each block forming portions of a track circuit and each track circuit controlling a circuit closer included in a signal circuit. The signal circuits overlap each other and are each provided with a pair of contact carrying members or devices, one of which is shown in Figs. 1 and 2, these contact carrying devices being located adjacent the track at the juncture of one block with the next. Each of these contact carrying devices includes a base or platform 39 which is mounted upon the extended ends of ties 40 which carry the rails 41 of the track. This base supports an electric motor 42 which is included in the signal circuit above referred to and forms an actuating means for moving the contact members of the device in and out of active position. The shaft of this motor is operatively connected with a shaft 43 journaled in spaced brackets 44 which also form bearings for a second shaft 45 disposed in parallel spaced relation to the first. These shafts carry the contact members 46 and 47, respectively.

The contact member 46 includes spaced heads 48 and 49 secured against rotation upon the shaft 43 adjacent the brackets, a cylindrical contact member 50 extending in parallel spaced relation to the shaft and connected at its ends to the heads and a counterweight 51 also extending in parallel spaced relation to the shaft and diametrically opposite the contact 50, this counterweight also being secured by its ends to the heads. In like manner, the contact member 47 includes heads 52 and 53 carrying a contact member 54 and counterweight 55, these parts being identical in construction to the corresponding parts of the contact member above described. The heads are connected by links in such a manner that any rotation of the shaft 43 will cause a corresponding rotation of the shaft 45. The motor is so arranged that when energized it will turn the shaft 43 and consequently the shaft 45 to hold the contact members with their counterweights uppermost, the swinging of said contact members, under the influence of the motor, being limited by the engagement of the contact 50 with a stop pin 56. As soon, however, as the motor 42 is deenergized the counterweights immediately swing the contact members to the position shown in Fig. 2 in which position they are blocked against further swinging by stops 57 carried by the brackets 44. All of the above described mechanism is preferably inclosed in a suitable casing or housing 58, that side of the housing against the tracks being opened for a reason which will be hereinafter apparent. The base 39 is provided at its forward edge adjacent each end with an upwardly directed standard 59 and these standards are connected immediately above and below the positions occupied by the upper and lower contacts, respectively, when swung to active position by outwardly bowed plates 60 and 61, the central portions of which extend parallel to the contacts, while the end portions are inclined inwardly to the standards to which they are firmly secured. The purpose of these arcuate or bowed plates will be later fully explained.

The circuit closers or brushes carried by the locomotive may be supported from any suitable part thereof, preferably from the bumper timber 62, one method being that shown in Fig. 2 of the drawings including a hanger 63 extending downwardly from one end of the timber and provided with spaced bearings 64 and 65 lined with vulcanized rubber, fiber or other suitable insulating material 66 through which are passed the inner ends of pipes 67 and 68, said pipe ends being provided with binding posts 69 and 70, respectively. The pipes terminate at their outer ends in heads 71 carrying blocks of insulating material 72 which in turn carries spring brushes or shoes 73. Secured about the outer end of each of the pipes 66 and 68 and surrounding, in spaced relation, the heads, insulating blocks and inner portion of the brushes, are cup-shaped metallic housings 74 so arranged that when the brushes 73 engage the contacts 50 and 54 of the contact carrying devices, they will be bent or sprung into engagement with the free edges of their respective housings 74, immediately springing out of such engagement when the brushes are disengaged from the contacts. The pipes 67 are secured against all sliding and turning movement in the hangers and are so proportioned and mounted that when the contacts of the con-

tact carrying devices are swung to active position, the brushes upon any locomotive will engage the said contacts. One pair of these brushes is extended from each side of the locomotive in order that at least one pair will be engaged by any contact members held in active position, irrespective of which side of the track the contact members are mounted upon or of which direction the locomotive is traveling along the track.

In order to protect the brushes from moisture, dirt, sleet or snow, I provide for each pair of brushes a housing 75, preferably formed of sheet metal and closed upon all sides, the outer faces of said housing being reentrantly formed to provide pockets 76 in which the brushes normally seat, the rear wall and the rear walls of these pockets are apertured for the passage of the brush carrying pipes 67 and 68 and the openings thus formed are lined with sleeves 77 and 78 of insulating material through which the pipes are slid able. The sleeves 77-78 are provided at their rear ends with radially directed flanges 79 and helical springs 80 are positioned one about each of the pipes 67 and 68 bearing between these flanges and collars 81 secured to the pipes by set screws 82, the function of these springs being to normally hold the housing in outward position to seat the brushes in the pockets thereof.

When a train approaches one of the contact carrying devices the forward portion of the brush housing upon that side of the track adjacent the contact carrying device is engaged by the inclined forward ends of the plates 60 and 61 of said device and forced inwardly along the brush carrying pipes to expose the brushes which, as previously explained, extend in the path of the contacts if they be in active position. As soon as the engine has passed, the springs immediately force the housing outwardly again to protect the brushes. It should be noted at this point that the brushes are completely insulated from the pipes supporting the same and that the brush housing 74 and pipes 67 and 68 are completely insulated from the main housing 75 and hangers 64.

Having thus described the mechanical construction and operation of all parts of my safety appliance I will now explain the wiring of the circuits by means of which the motor controlling the engineer's valve is operated by the engagement of the brushes with the contacts of the contact carrying devices of the block signal system.

A conductor wire 83 leads from the generator to the forward portion of the locomotive and is electrically connected by a wire 84 with the binding posts 70 of each of the pipes 68 and consequently with each of the housing cups 74 of the lower brushes 73.

A conductor wire 85 has its ends, which are insulated, passed through the pipes 68 of the brush holders and electrically connected to the lower brushes 73, being secured in place by set screws 85'. A conductor wire 70 75 connects this wire 85 with the motor 28, while a conductor wire 87 connects the motor with a conductor wire 88. This latter wire leads by its ends through the pipes 67 and is electrically connected to the brushes 75 supported by said pipes. A wire 89 connects the binding posts 69 of the pipes 67 and a wire 90 leads from this wire 89 to the generator or dynamo 20. It will therefore be apparent that each of the brushes and each of the cup-shaped housings or casings of each pair of the brushes form parts of a circuit through the dynamo and motor, the circuit being normally open between the upper brush and housing of each pair and also between the lower brush and housing of each pair.

In operation, assuming that the train is moving along the track, with the valve 21, controlling the passage of steam to the turbine, open and with the turbine and dynamo both in motion, if the locomotive passes a contact carrying device in which the contacts are in active position its brushes engaging against the contacts will be momentarily sprung against the sides of their respective housings and the following circuit closed: Current passing from the generator or dynamo through the wire 83 and wire 84 to the housing of the lower brush, from said housing through the engaging brush, from said brush to the wire 85, through said wire and the wire 86 to the motor, through the motor, wire 87 and wire 88 to the upper brush from the upper brush to the housing 74 thereof and along the pipe 67 to the wire 89 and so through the wire 90 back to the dynamo. It will therefore be apparent that the circuit thus momentarily closed through the dynamo and motor will start the motor and cause the same to move the engineer's valve to service position and so apply the air brakes. The contacts 50 and 54 should of course be of sufficient length to insure a long enough closing of the circuit to cause a sufficient length of operation of the motor, a short time however, is sufficient for this.

It will of course be understood that the wiring illustrated in Fig. 1 is wholly diagrammatic and that in practice all of these wires will be heavily insulated and preferably inclosed in conduits. It will further be understood that the current generated by the dynamo may be utilized for other purposes beside that of actuating the motor as it may be employed for service current for other signaling devices about a train, for lighting or other purposes, if desired.

The above described mechanism is not at

all complicated and may be readily installed at small cost and when employed in connection with a suitable block signal system should afford absolute protection to trains 5 under all circumstances.

It will of course be understood that I do not wish in any way to limit myself to the specific details of construction, or arrangement of parts, illustrated and described in 10 this application, as various minor changes within the scope of the appended claims, may be made at any time, if desired, without in the slightest degree departing from the spirit of my invention.

Having thus described the invention, what is claimed as new is:

1. In an appliance of the character described, the combination with an engineer's valve, of a normally open circuit, means in 20 the circuit adapted when the latter is closed to operate the engineer's valve, and circuit closers in the circuit adapted for engagement with track contacts when the said contacts are moved to active position, said circuit closers each including a housing electrically connected in the circuit and a brush mounted within the housing, electrically connected in the circuit and adapted upon engagement with a contact to move into electrical engagement with the housing.

2. In an appliance of the character described, the combination with an engine having an engineer's valve, of a hanger carried by the engine, conduits carried by the hanger 35 and extending laterally from the engine, a housing slideable upon the conduits and having its outer wall formed with pockets through which the conduits extend, a brush housing mounted upon the free end of each conduit, a brush mounted in each brush housing and insulated therefrom but adapted upon engagement with track contacts to move into contact with the brush housing, means for normally holding the housing 40 mounted upon the conduits in extended position to seat the brush housings and brushes in their pockets, a circuit including both brush housings and both brushes, and means operable by the closing of the circuit for operating the engineer's valve.

3. In an appliance of the character described, the combination with an engine having an engineer's valve, of a hanger carried by the engine, conduits carried by the hanger 55 and extending laterally from the engine, a housing slideable upon the conduits and having its outer wall formed with pockets through which the conduits extend, a brush housing mounted upon the free end of each conduit, a brush mounted in each brush housing and insulated therefrom but adapted

upon engagement with track contacts to move into contact with the brush housing, means for normally holding the housing mounted upon the conduits in extended position to seat the brush housings and brushes in their pockets, said means including collars mounted about the conduits and within the housing and springs surrounding the conduits and engaging between the collars and the inner face of the outer wall of the housing, a circuit including both brush housings and both brushes, and means operable by the closing of the circuit for operating the engineer's valve.

4. In an appliance of the character described, the combination with swingingly mounted track contacts and arcuate plates positioned adjacent the contacts, of a locomotive having an engineer's valve, circuit closers carried by the locomotive and adapted for engagement with the contacts, a housing normally inclosing the circuit closers and adapted for engagement with the plates for movement away from the circuit closers, 85 a circuit through said circuit closers, and means operable by the closing of said circuit closers by engagement with the contacts for operating the engineer's valve.

5. In an appliance of the character described, the combination with an engineer's valve, of a normally open circuit, means in the circuit adapted, when the latter is closed, to operate the engineer's valve, a fixed contact in the circuit, a movable contact in the 95 circuit adapted for engagement with the fixed contact by engagement with a track contact, and a housing normally surrounding the contacts and movable to expose the same.

6. In an appliance of the character described, the combination with an engineer's valve, of conduits adapted for support upon an engine, a housing slideable upon the conduits and formed with pockets through which the conduits extend, a brush housing mounted upon the free end of each conduit, a brush mounted in each brush housing and insulated therefrom, the brushes being movable into engagement with their housings 110 upon engagement with track contacts, means including a circuit through the brushes and housings for controlling the engineer's valve, and means for normally holding the housing mounted upon the conduits in position 115 to seat the brush housings in their pockets.

In testimony whereof I affix my signature in presence of two witnesses.
